UNITED STATES PATENT OFFICE.

AUGUST J. FONDEVILLE, OF EAST ORANGE, NEW JERSEY.

DESIGN FOR A PLATE OR SIMILAR ARTICLE.

48,468.

Specification for Design.

Patented Jan. 18, 1916.

Application filed October 26, 1915. Serial No. 58,087. Term of patent 7 years.

To all whom it may concern:

Be it known that I, AUGUST J. FONDEVILLE, a citizen of the United States, residing at East Orange, in the county of Essex and State of New Jersey, have invented a new, original, and ornamental Design for a Plate or Similar Article, of which the following is a specification, reference being had

to the accompanying drawings, forming a part thereof, and in which—

Figure 1 is a top plan view, and Fig. 2 an edge view of a plate embodying my design.

I claim:

The ornamental design for a plate or similar article, as shown.

AUGUST J. FONDEVILLE.

Copies of this patent may be obtained for five cents each, by addressing the "Commissioner of Patents, Washington, D. C."
